DESIGN FOR A READING GLASS

Louis F. Chapoton, Detroit, Mich.

Application March 4, 1940, Serial No. 90,664

Term of patent 14 years

To all whom it may concern:

Be it known that I, Louis F. Chapoton, a citizen of the United States, residing at Detroit, in the county of Wayne and State of Michigan, have invented a new, original, and ornamental Design for a Reading Glass, of which the following is a specification, reference being had therein to the accompanying drawing, forming part thereof.

Figure 1 is a front elevational view of a reading glass, showing my new design;

Fig. 2 is an elevational view looking at one edge of the reading glass;

Fig. 3 is a vertical sectional view taken on the line 3—3 of Fig. 1, and

Fig. 4 is a horizontal sectional view taken on the line 4—4 of Fig. 3.

I claim:

The ornamental design for a reading glass, as shown.

LOUIS F. CHAPOTON.
